CONCRETE FORM

James W. McDonnell, Stanford, Calif.

Application August 9, 1948, Serial No. 43,227

5 Claims. (Cl. 25—131)

1

This invention relates generally to forms for use in making concrete structures, and particularly cylindrical shaped structures such as are usable as manholes for subterranean electrical distribution systems.

It is an object of the invention to provide a concrete form which is usable for the purposes indicated above, and which in particular facilitates the work of removing the walls of the form from the poured concrete after the concrete has hardened.

A further object of the invention is to provide a concrete form of the above character which can be reused indefinitely, and which can be readily positioned for a pouring operation, as well as readily removed after the concrete has hardened.

Another object of the invention is to provide a concrete form of the above character having both inner and outer metal walls, cylindrical in contour, and which is provided with means for effectively separating the walls from the sides of the concrete to facilitate removal after the concrete has hardened.

Additional objects of the invention will appear from the following description in which the preferred embodiment has been set forth in detail in conjunction with the accompanying drawing.

Referring to the drawing:

Figure 1 is a side elevational view illustrating a concrete form incorporating the present invention.

Figure 2 is a cross-sectional view of the same form illustrated in Figure 1, but showing the parts disposed in an excavation ready for a pouring operation.

Figure 3 is a plan view of the form as illustrated in Figure 1, certain parts being broken away and certain parts being shown in section.

Figure 4 is an enlarged cross-sectional detail taken along the line 4—4 of Figure 1.

Figure 5 is an enlarged cross-sectional detail taken along the line 5—5 of Figure 1.

Figure 6 is an enlarged cross-sectional detail taken along the line 6—6 of Figure 1.

Referring first to Figures 1 to 3 inclusive, my form comprises inner and outer cylindrical metal walls 11 and 12, which are disposed in alignment to form the annular pouring space 13. Normally these walls are disposed in upright relation in an earth excavation 14 (Figure 2) to enable one to pour a circularly contoured annular wall.

The inner wall 11 can be formed of a single piece of steel bent into cylindrical form, and with an overlapping junction 16 for the adjacent

2

vertical edges. This junction can be formed by a vertical metal strip 17 which is secured as by welding to the adjacent edge 18 of the sheet metal, and arranged to overlap the adjacent edge portion 19. Normally there is a substantial gap between the edge portions 18 and 19, to permit the wall 11 to contract somewhat by the use of means to be presently described.

Vertically disposed members 21, such as steel angles, are attached to the wall 11 at circumferentially spaced points as illustrated in Figure 3. At the lower end of the form there are two pairs of radially extending members 22 and 23, the two pairs being at right angles to each other. The outer ends of these members are pivotally attached at 24 to the vertical members 21. The inner ends of the members 22 and 23 have pivotal connections 26 with the lower end of a vertical member 27, which extends axially of the form. At the upper end of the form similar radially extending members 28 and 29 are provided, which have their outer ends pivotally attached at 31 to the upper ends of the vertical members 21, and their inner ends pivotally attached by pins 32 to the vertical member 27. Similarly, intermediate the upper and lower ends of the form radially extending members 36 and 37 are provided, which are pivotally attached at 38 to the vertical members 21 and pivotally attached at 39 to the central vertical member 27.

Near the upper end of the form, but below the members 28 and 29, cross-struts 41 and 42 are provided, which extend at right angles to each other and which are disposed immediately below the members 28 and 29. Members 41 and 42 are secured together by suitable means such as the bolt or rivet 43. The outer ends of the members 41 and 42 are connected to the corresponding ends of the members 28 and 29 by the links 44 and 46. Similar members 47 and 48 are provided below the members 36 and 37, and these members likewise connect with the outer ends of members 36 and 37, by the links 49 and 51.

The upper end of the member 27 is provided with a suitable hoist ring 52 for convenient attachment to a hoisting appliance. It will be evident that when the member 27 is pulled upwardly from the position shown in Figure 2, the inner ends of the members 28, 29, together with the members 22, 23 and 36, 37, will be moved upwardly, and as a result the outer ends of these members will pull inwardly on the vertical members 21, and on the wall 11 to which these members are attached. As a result the inner wall is caused to collapse to the limit of the movement

permitted by the dimensioning of struts 41, 42, 47 and 48. The amount of permitted contraction is such that it enables the inner wall 11 to be freed from hardened concrete, and to permit its removal.

The outer wall 12 is preferably made in a plurality of sections 12a, 12b, 12c and 12d. Sections 12a and 12b are attached together by special means to be presently described. The remainder of the sections are secured together by suitable means such as the upper and lower brackets 53 and 54, which are retained together by the clamping bolts 56 and 57.

Special means is provided to enable expansion of the outer wall 12, and preferably this means operates in conjunction with upward pull upon the vertical member 27. Thus a metal ring 58 is provided which generally embraces the upper part of the form, and which is made of suitable material such as a steel channel. Circumferentially spaced parts on this ring, 90° apart, are loosely connected to the outer ends of the radially extending rods 61. The inner ends of these rods are provided with eyes 63 which engage the studs 64 carried by the upper end of member 27. Circumferentially spaced points on the ring 58, intermediate the point of connection with rods 61, are attached by pads 65 to intermediate points on the outer wall sections 12a, 12b, 12c and 12d. The ring 58 has a certain amount of spring, so that when circumferentially spaced points on the same are sprung inwardly by inward pull exerted by rods 61, the portions of the ring attached to pads 65 tend to spring outwardly to thereby expand the outer form.

Additional means connecting the wall sections 12a and 12b enables these sections to be positively forced apart when upward pull is applied to member 27. Thus connecting means is provided between the lower portions of wall sections 12a and 12b, including the brackets 66, which are drilled to loosely accommodate the retaining bolt 67. Brackets 66 are yieldably urged together by the compression spring 68.

A vertical member 69 extends upwardly along the junction between the wall sections 12a and 12b, and this member may be a suitable structural steel channel as shown in Figure 5. It is pivotally attached at vertically spaced points 71 and 72, to the adjacent edges of the wall sections 12a and 12b. These pivotal connections are two studs 73 and 74 (Figure 6) which in turn are mounted upon the adjacent edge portions of the wall sections. With connections to the adjacent wall sections, as described, it will be evident that when the upper end of the member 69 is moved to the left, as viewed in Figure 1, the adjacent wall sections 12a and 12b will be forced away from each other.

Camming means is associated with the upper end of member 69, and can be constructed as follows: An additional member 76, which may be in the form of a structural steel channel, is located near the upper end of member 69, but spaced outwardly from the same (see Figure 4). Spacer members 77 are carried by member 76, and engage the outer peripheral portion of the ring 58 between the upper and lower flanges of the same. Apertures 78 and 79 are provided in the ring 58 and member 76 to loosely accommodate the adjacent pull rod 61. The retaining nut 81 on rod 61 engages the member 76 so that when rod 61 is pulled inwardly, member 76 applies inward thrust upon ring 58.

Extending along the junction between the wall

sections 12a and 12b, there is a vertical overlap strip 82, which is secured to wall 12a as by welding, and which extends in overlapping relation with the wall section 12b. Strip 82 and the member 76 carry cam blocks 83 and 84 (Figure 5) which are provided with inclined cam faces 86 and 87. These cam blocks cooperate with cam blocks 88 and 89, which are mounted upon the member 69. With the arrangement just described it will be evident that when member 76 is caused to move inwardly toward the cam block 83, the two cam blocks 83 and 84 press upon the blocks 88 and 89, to force the latter together with member 69 to the left as viewed in Figure 5. As previously pointed out movement of the upper end of the member 69 to the left, as viewed in Figure 1, serves to force the two wall sections 12a and 12b apart.

The use of my concrete form can be explained as follows: It is installed in a ground excavation substantially as shown in Figure 2. If desired a bottomwall can be poured before the form is installed, or this wall may be left for pouring after the side walls have been made. With all of the parts as illustrated in Figures 1 and 2, the inner wall 11 is expanded to proper dimensions, and the outer wall 12 is held to its proper diameter. The space 13 between the inner and outer walls is now poured with the concrete, and as is known to those familiar with the pouring of concrete structures, suitable vibrators and like appliances can be used in order to insure proper density. After the concrete has hardened the clamping bolts 56 and 57 are loosened, and suitable hoisting means is applied to the ring 58. This ring, together with member 27, is then lifted. Upward movement of member 27 causes raising of the members 28, 29, 36, 37 and 22, 23 to contract the inner wall 11, thus breaking any adhesion between this wall and the concrete, and contracting the inner wall to such dimensions that it may be readily removed. Contraction of the inner wall 11 is limited by engagement of this wall with the ends of the struts 41, 42 and 47, 48.

Upward movement of member 27 also causes inward pull to be applied by the rods 61 to circumferentially spaced points of the ring 58. As previously pointed out these points spring inwardly, causing outward forces to be applied through pads 65 to expand the wall sections 12a, 12b, 12c and 12d. At the same time such springing of the ring 58 moves the member 76 inwardly with the result that cam block 84 moves toward cam block 83, thus shifting the upper end of member 69 to the left as viewed in Figure 5, due to the camming action through the blocks 88 and 89. As previously explained such movement of the member 69 acts through the pivotal connections 71 and 72 to positively force the wall sections 12a and 12b apart.

Upon completion of the operations described above all of the wall sections should be detached from the concrete, whereby further upward pull upon the ring 58 serves to elevate the form free of the poured structure. It should be understood however that conventional methods can be used to assist breaking any adhesion between the walls and the concrete, as for example application of pneumatic hammers or the like.

It will be seen from the foregoing that I have provided a complete form which provides both the outer and inner walls used in pouring a cylindrical manhole. The arrangement is such that by applying force to a single member, both the inner and outer walls are detached from the

hardened concrete, to permit removal of the form as a complete unit.

I claim:

1. In a concrete form construction, a substantially cylindrical shaped outer wall, said wall being provided with a longitudinally extending junction permitting expansion of the wall, a longitudinally extending member exterior of said wall and extending along said junction, said member having vertically spaced points of pivotal connection to the wall sections adjacent said junction, and means for swinging said member about said pivotal connections to thereby expand said wall.

2. A form as in claim 1 in which said last named means comprises cam means acting between said member and said wall.

3. In a concrete form construction, a substantially cylindrical shaped outer wall, said wall being provided with a longitudinally extending junction formed to permit expansion of the wall, a member extending axially of said wall, and adapted to be moved longitudinally, a ring generally embracing the upper portion of said wall, means connecting circumferentially spaced points of said ring to sections of the wall, and means connecting other circumferentially spaced points of said ring to said centrally located member, said other points being located intermediate said first named points on the ring, whereby longitudinal movement of said axially located member serves to spring portions of said ring inwardly and the other portions connected to the sections of the wall to spring outwardly to thereby expand the wall.

4. In a concrete form construction, a substantially cylindrical shaped outer wall, said wall being provided with a longitudinally extending junction formed to permit expansion of the wall, a ring generally embracing the upper portion of the wall, means serving to connect circumferentially spaced points on said ring with sections of said wall, an axially located member movable longitudinally, pull rods connecting said axially located member with other circumferentially located points of said ring, said other points being located intermediate said first named points, a member extending generally longitudinally of the junction, said member having spaced points of pivotal connection with wall sections adjacent

said junction whereby swinging of said member serves to move said wall sections apart, and cam means acting between said ring and one end portion of said member and serving to swing said member about said pivotal connections responsive to longitudinal movement of said first named member to spring the ring.

5. In a concrete form construction, inner and outer substantially cylindrical shaped walls spaced apart to form a pouring space, a member extending axially of said walls and adapted to be moved longitudinally upon application of forces to the same to lift the entire form, radially extending means connecting said member with said inner wall whereby longitudinal movement of said axially located member serves to apply forces to contract the inner wall, means for limiting the extent of contraction of the inner wall, a ring generally embracing the upper portion of the outer wall, means serving to attach circumferentially spaced points on said ring with circumferentially spaced points of the outer wall, means connecting said axially located member with other circumferentially spaced points of said ring, said other points being located intermediate said first named parts, pull upon said other parts serving to spring the ring from circular contour whereby the points connected with the wall sections serve to expand the latter, a junction formed in the outer wall section and extending generally longitudinally of the same, said junction being formed to permit expansion of the wall sections adjacent the same, and additional means including cam elements serving to move said last named wall sections apart upon applying movement to said axially extending member to expand the inner wall and to spring said ring.

JAMES W. McDONNELL.
